(57) **CLAIM**

The ornamental design for a cleaning pad, as shown and described.

DESCRIPTION

FIG. 1 is a top, front, left perspective view of a cleaning pad (such as for use in a mobile cleaning robot), showing our new design;

FIG. 2 is a top, rear, right perspective view thereof;

FIG. 3 is a bottom, front, left perspective view thereof;

FIG. 4 is a bottom, rear, right perspective view thereof;

FIG. 5 is a front view thereof;

FIG. 6 is a rear view thereof;

FIG. 7 is a right side view thereof;

FIG. 8 is a left side view thereof;

FIG. 9 is a top view thereof; and,

FIG. 10 is a bottom view thereof.

The shade lines show surface contour and not surface ornamentation.

Features shown in dashed lines represent unclaimed portions of the cleaning pad and form no part of the claimed design.
